No. 798,892.

PATENTED SEPT. 5, 1905.

C. W. EVANS.

RATCHET STOCK AND DIE.

APPLICATION FILED FEB. 25, 1905.

UNITED STATES PATENT OFFICE.

CHARLES W. EVANS, OF MEGE, NORTH CAROLINA.

RATCHET STOCK AND DIE.

No. 798,892.

Specification of Letters Patent.

Patented Sept. 5, 1905.

Application filed February 25, 1905. Serial No. 247,335.

To all whom it may concern:

Be it known that I, CHARLES W. EVANS, a citizen of the United States, residing at Mege, in the county of Chowan and State of North Carolina, have invented new and useful Improvements in Ratchet Stocks and Dies, of which the following is a specification.

This invention relates to ratchet stocks and dies of the type employed for cutting threads, and has for its objects to produce a comparatively simple inexpensive device of this character in which the cutting-dies may be readily interchanged, one wherein the ratchet-head carrying the die may be driven in either direction, and one in which the pawls adapted for operating the head may be turned to and securely locked in inactive position.

With these and other objects in view the invention comprises the novel features of construction and combination of parts more fully hereinafter described.

In the accompanying drawings, Figure 1 is a plan view of a device embodying the invention. Fig. 2 is a view partly in section, the 25 section being taken on the line 2 2 of Fig. 4. Fig. 3 is a side elevation of the ratchet-head and adjacent parts. Fig. 4 is a section taken on the line 3 3 of Fig. 1. Fig. 5 is a side elevation showing the manner of removing or inserting the dies into the ratchet-head. Fig. 30 6 is a detail side elevation of the wrench carried at one end of the stock. Fig. 7 is a detail view of the wrench-head.

Referring to the drawings, 1 designates a stock or handle provided at one end with a pair of spaced annular jaws 2 and 3, of which the jaw 2 is fixed, while the jaw 3 is pivoted at 4 to a bracket-arm 5, fixed upon the jaw 2, the jaw 3 being adapted to swing to open or 40 closed position and to be locked in the latter position by means of a thumb-screw or other fastening member 6, threaded through an ear 7, which fits flush within a correspondingly-shaped socket or recess 8, formed in the stock 45 1. The jaws 2 and 3 are adapted to receive between them for rotation a die 9, provided with internal thread-cutting members 10 and with an external peripheral flange or projection 11, disposed centrally between the ends 50 of the die, and having formed at its marginal edge ratchet-teeth 12, adapted for engagement by pawls 13, pivoted, respectively, adjacent opposite edges of the stock and within a recess 14, formed in the latter, there being 55 extended into said recess leaf-springs 15, which bear, respectively, upon the pawls. Each of

the pawls 13 is formed, as seen more clearly in Fig. 2, with an engaging portion 16 to enter between the ratchet-teeth 12 and has its end edge adjacent the pivot beveled or inclined, as at 17, for engagement by one of the springs 15 to hold the pawl in ratchet-engaging position, the spring being adapted when the pawl is thrown to inactive position to bear on one of the longitudinal edges of the pawl, 65 thereby locking the latter in such position.

In practice the stock will be accompanied by a set of dies 9 for operation upon bodies of different diameters and for cutting threads of different pitch, and these dies may be 70 readily interchanged when circumstances require and, as will be obvious, by manipulating the thumb-screw 6 to release the movable jaw 3 and permit of the latter being swung to the position illustrated in Fig. 5. 75 When seated in the head between the jaws, the die may be rotated by engaging one or the other of the pawls 13 therewith, it being understood, of course, that the direction of rotation of the die will accord with the particular pawl which is brought into action, and, further, that the springs 15 subserve the twofold function of locking the pawls in either their active or inactive positions.

The normally rear end of the stock 1 is 85 formed with a pair of spaced annular jaws which receive between them for rotation a rotary wrench-head 18, provided with a nut engaging opening 19 and having a flange 20, on the periphery of which is formed ratchet-teeth 90 21, designed for engagement by either of a pair of pawls 22, designed to be maintained in active or inactive position through the medium of leaf-springs 23, the pawls 22 and springs 23 being identical in form and construction with the corresponding parts 13 and 15 heretofore described, it being apparent that in action the head 18 will be rotated in either direction according to the particular pawl which is brought into play, as in the instance of the die-heads 9 above described. 95 100

From the foregoing it is apparent that I produce a simple inexpensive device admirably adapted for the attainment of the ends in view, it being understood that minor 105 changes in the details herein set forth may be resorted to without departing from the spirit of the invention.

Having thus fully described the invention, what is claimed as new is— 110

In a device of the class described, a stock having a recess formed in one face thereof and

provided with a pair of spaced annular jaws, one of said jaws being fixed and the other movable, a bracket-arm carried by the fixed jaw and having the movable jaw pivoted thereto to swing toward and from the fixed jaw, a rotatable head removably seated between the jaws and provided with ratchet-teeth, a pawl carried by the stock and designed to coöperate with the ratchet-teeth for rotating the head, an ear provided on the movable jaw to fit in the recess in, and flush

with the face of, the stock, and a fastening member threaded through the ear and into the stock for securing the jaw in closed position.

15

In testimony whereof I affix my signature in presence of two witnesses.

CHARLES W. EVANS.
